REFRIGERATED DISPLAY CASE

Ernest E. Sanders, Detroit, Mich.

Application August 30, 1939, Serial No. 292,691

4 Claims. (Cl. 62—89.5)

The present invention relates to refrigerated food display cases, particularly designed for the display of fresh vegetables though they may be used for other foods if desired.

Among the objects of the invention is a refrigerated display case of the "self-serve" type, in which a customer may inspect and select without the presence of a store attendant.

Another object is a display case of this type which may remain open without a substantial decrease in efficiency.

Still another object is a display case in which none of the contents is more than a few inches distant from a cooling element.

Other objects will readily occur to those skilled in the art upon reference to the following description and the accompanying drawings in which

Figure 1 is a perspective view of a display case involving the invention.

Figure 2 is a vertical section through the case.

Figure 3 is a sectional view through one of the partitions.

Figure 4 is a perspective view of the refrigerating element.

Figure 5 is a view of the header with the cover removed, and

Figure 6 is a section on line 6—6 of Figure 2.

In the drawings the case is shown as being conventionally constructed at the bottom and ends, in that it has outer and inner sheathing 10—11 with insulation 12 between them. The rear wall of the case is likewise constructed and is without the usual doors, these, 13, being in the low front wall 14.

Supported by the low front wall and the back wall is an inclined partition 15, forming the ceiling of the storage compartment 16 in the lower part and the bottom or floor of the display section 17, upon which may be placed removable false bottom members 15b.

The display section 17 is surrounded by the back wall, the ends of the case, and a glass front 20 extending upward from front wall 14 to approximately the height of the rear wall, while the open top thus provided is partially covered by a glass cover member 21, leaving a large opening 22 through which easy access to the interior of space 17 may be had.

Refrigeration of the storage compartment 16 may be had by mounting upon the walls thereof one or more refrigerating coils 25.

As will be seen best in Figures 1 and 6, the space 17 will be divided, in its lower part upon the floor 15, into a plurality of bins or sections

30, by fixed partitions 31 and the bins 30 may be subdivided by movable partitions 32.

The fixed partitions 31 form a part of the refrigerating means for compartment 17 and in order to do so are made of sheet metal and hollow, as indicated in Figures 3, 4 and 6, and serve as containers for brine, alcohol, or other cold storage liquid 35.

Partitions 31 open into a header 36 in which is located a refrigerating coil 37, the header, containing the coil, and the partitions being constructed to form a unit and after filling with the cold storage liquid, sealed except for the pipe leads 37a connected to a suitable compressor unit.

The sealed refrigerant unit, shown in Figure 4, is placed in compartment 17 and supported in such fashion that it is inclined as shown in Figure 2 and is spaced a short distance from floor 15. (See Fig. 3 at 15a.) By so placing the unit in an inclined position, efficient circulation of the liquid in the partitions and of air around the partitions is assured.

It will be noted that the opening 22 through which access is had to compartment 17 is at substantially the extreme height of the case and horizontally placed, while a suitable closure may obviously be provided, it is however, possible to leave this open without substantial interference with the maintenance of suitable temperatures in the compartment 17, since there can be little or no outflow of the heavier cold air.

The arrangement of doors 13 in the front wall permits positioning of the case against a building wall while allowing access to compartment 16.

Now having described the invention and a preferred embodiment thereof, what is claimed is:

1. In a refrigerated display case having heat insulated walls enclosing its bottom and sides and divided into an upper and lower compartment, refrigerating means in the upper compartment, said means being in the form of a header having downwardly inclined parallel, relatively thin, wide members, said header and members dividing said upper compartment into a plurality of inclined bins.

2. In a refrigerated display case, an upper, at least partially glass-enclosed compartment having an opening in its upper portion, the edges of said opening being in a substantially horizontal plane, means for dividing said compartment into a plurality of bins, said means consisting of hollow partition members, a header with which said members are connected, and a refrigerating coil

in said header, the coil, header and members constituting a unitary structure, said header and members having sealed therein a body of cold storing liquid.

3. In a refrigerated display case, a display compartment having vertical side walls the upper edges of which are in a substantially horizontal plane, and having an inclined floor, said compartment being divided into a plurality of bins, hollow partitions constituting the dividing means and arranged in an inclined position adjacent said floor, a header into which the hollow partitions open, said header extending lengthwise of the case at the upper ends of said partitions, said header and partitions being substantially filled 15

with cold storage liquid, and a refrigerating coil enclosed in said header.

4. A refrigerated display case having its side walls terminating at the top in a substantially horizontal plane and divided into a lower and an upper compartment, the dividing means being sloped toward the front, means for dividing the upper compartment into a plurality of bins, the latter means consisting of hollow sheet metal partitions enclosing refrigerant, and heat insulating means constituting the rear, end and bottom walls of said case and the front wall of the lower compartment, the front wall of the upper compartment being of transparent material.

ERNEST E. SANDERS.
